Inventor:
V. E. Rowland
By May A. Schmidt
Attorney.

UNITED STATES PATENT OFFICE.

VALSY E. ROWLAND, OF INDIANAPOLIS, INDIANA.

FLOOR STRUCTURE.

1,424,422.

Specification of Letters Patent. Patented Aug. 1, 1922.

Application filed January 3, 1922. Serial No. 526,650.

To all whom it may concern:

Be it known that I, VALSY E. ROWLAND, a citizen of the United States, residing at Indianapolis, in the county of Marion and 5 State of Indiana, have invented certain new and useful Improvements in Floor Structures, of which the following is a specification.

This invention relates to floor structures, 10 and its object is to provide a novel and improved structure of this kind composed of hollow blocks or tiles, and concrete or other analogous material, and also to provide a floor structure which is cheap and possesses 15 great strength and durability.

Other objects and advantages of the invention will be pointed out in the detailed description appearing hereinafter, and in order that the invention may be better understood, reference is had to the accompanying drawing forming a part of this specification.

In the drawing,

Figure 1 is a perspective view of one of 25 the hollow blocks or tiles; Fig. 2 is a sectional view of a floor in which the block shown in Fig. 1 is used, and Fig. 3 is a perspective view of a spacing element.

In carrying out the invention, there is 30 provided a hollow building block composed of parallel bottom and top walls 10 and 11, parallel end walls 12 and 13, an integral longitudinal web 14 extending between the end walls parallel to the bottom and top 35 walls, and transverse webs 15 extending between the bottom and top walls and the longitudinal web parallel to the end walls. The block is made of clay, concrete or any other suitable material usually employed in 40 the construction of building blocks, and it can be made in various sizes. The webs 14 and 15 define a series of cells 16 located on one side of the web 14, and another series 17 located on the other side of said web. 45 These cells extend horizontally through the block and open through the sides thereof.

Fig. 2 shows the wall block of Fig. 1 employed in a floor construction. Here the blocks are laid in horizontal rows and in 50 endwise spaced relation to bring the grooves 18 of adjacent blocks opposite each other. The blocks are retained in spaced relation by spacers 19 which bridge the blocks at the bottom and are supported by having their 55 ends seating the bottom grooves 18, said ends being reduced to bring the bottom surface of the spacers flush with the bottom

surface of the blocks. On top of the blocks is placed the layer 20 of concrete forming the floor surface, said material also being 60 poured between the blocks to form the floor joists or beams 21, which latter may be provided with a reinforcement 22. The spacers 19 close up at the bottom the spaces between the blocks, and serve as a moisture absorbing 65 surface between the concrete material forming the joists and the plaster or other ceiling material 23, and they also assure the same width of all the joists. The end grooves 18 of the blocks produce an irregular 70 surface to which the concrete material forming the floor joists firmly adheres, and the blocks are securely interlocked with and united to the joists. The reduced ends of the spacers 19 do not occupy the bottom 75 grooves entirely, so that the concrete material forming the joists may enter said grooves above the ends of the spacers and bond the same in place.

I claim:

1. A floor structure comprising blocks laid in rows and spaced at their ends, a layer of plastic material on said blocks, said material also filling the spaces between the ends of the blocks to form floor joists, and 80 spacing elements between the blocks at the bottom thereof, the ends of the blocks having transverse grooves in which the ends of said elements seat and are supported, and said block ends having other transverse 85 grooves entered by the material forming the joists, said ends of the spacing elements filling only portions of the first mentioned grooves to permit the joist material to enter 90 said grooves above said ends of the spacing 95 elements.

2. A floor structure comprising blocks laid in rows and spaced at their ends, a layer of plastic material on said blocks and also filling the spaces between the ends thereof to 100 form floor joists, and spacing elements between the blocks at the bottom thereof, the ends of the blocks having grooves in which the ends of the spacing elements seat and are supported, and said ends being reduced 105 in thickness to partly fill the grooves and locate the bottom surfaces of the spacers flush with the bottom surfaces of the blocks, the spaces in the grooves above the reduced ends of the spacing elements being also 110 filled with the aforesaid joist material.

In testimony whereof I affix my signature.

VALSY E. ROWLAND.
